UNITED STATES PATENT OFFICE.

MORITZ HAMMERSTEIN, OF BERLIN, GERMANY, ASSIGNOR TO MAX BLAU,
OF BERLIN, GERMANY.

CANDLE-HOLDER.

SPECIFICATION forming part of Letters Patent No. 711,624, dated October 21, 1902.

Application filed October 25, 1901. Serial No. 79,950. (No model.)

To all whom it may concern:

Be it known that I, MORITZ HAMMERSTEIN, a subject of the Emperor of Germany, and a resident of Berlin, Germany, have invented 5 certain new and useful Improvements in Candle-Holders, of which the following is a description.

The present invention relates to hand-lamps; and it consists of the details of construction hereinafter set forth, and particularly pointed out in the claims.

In order to render the present specification easily intelligible, reference is had to the accompanying drawings, in which similar letters of reference denote similar parts throughout the several views.

Figure 1 is a side elevation of the lamp with the cover thrown back and the small glow-lamp projected out through the orifice in the 20 lamp-top. Fig. 2 is a plan view showing the whole top cover of the lamp thrown open to exhibit the arrangement of the parts; and Fig. 3 is a vertical section through the front part of the lamp, taken longitudinally.

25 The body of the lamp *k'* is advantageously of the antique form, and in the forward part of the same, beneath the main or lamp-body cover *k*, a small glow-lamp *a* is pivotally supported on a pin *m*, around which a coiled 30 spring *m'* is fixed, adapted to normally project the lamp *a* out through an opening in the cover *k*, Fig. 1. The lamp-body is provided with a fixed handle *d'* and a movable handle *d*. The latter is pivotally supported on the 35 cover *k* at *c* and has its arm *b* projecting through a guide-strip *h* and extending toward the front part *n* of the lamp with its slightly-bent finger *e'*. The orifice in the cover of the lamp-body is normally closed by a small cover 40 *f*, having a spring coiled around its hinge-pin *m'*, which acts to normally throw the small cover open. The cover *f* is held closed by a flat spring *e*, fixed to the interior of the said cover and having one end loose, so that the 45 said flat spring *e* presses against the edges of the orifice when the cover is closed and retains it closed by friction. The lever *b d* is provided with a spring-arm *g*, which normally holds the arm *b* against the opposite side of 50 the guide-strip and keeps the nose *e'* out of contact with the loose end of the flat spring *e*.

One of the poles of the lamp *a* is in connection with the metallic cover of the lamp-body, which is connected up to one of the poles of a small dry battery *o'* by means of 55 the contact-spring *i*, which makes contact with the cover *k* of the lamp when the latter is closed. The other pole *o* of the lamp is connected up to a contact-piece *k²*, which is insulated from the body of the lamp by a layer 60 of suitable insulating material *k³*. The piece *k²* carries an open contact *l*, and the lamp is provided with a spring projection *l'*, which when it is turned up contacts with *l* and joins the circuit, so that the lamp will glow. 65

The manipulation of the device is very simple. On pressing the movable handle *d* toward the fixed handle *d'* the nose *e'* will be forced against the loose end of the flat spring *e*, thus pressing the same back from the edges 70 of the orifice in the cover and releasing the small cover *f*, which will fly back under the influence of its spring. At the same moment the small lamp *a* being released from the pressure of the cover *f* also stands up in the 75 orifice of the cover, and owing to the contacts having been made in the manner previously described the lamp will glow and give light. On releasing the handle *d* the spring *g* pushes the nose *e'* back, so that on closing the cover *f* 80 the spring *e* will hold the same closed by friction.

I claim as my invention—

1. In a lamp the combination of a hollow body having means therein for producing an 85 electric light, a spring-opened cover in the top of the same and means for retaining it closed, an electric glow-lamp mounted beneath the said cover and means for throwing the same up into a vertical position extending out of the cover-orifice when the cover is opened and means, operated by the handle of the lamp to release the said cover and allow it to open when light is required.

2. In a lamp the combination of a body having an electric battery mounted therein, a spring-opened cover in the top of the lamp and means for retaining it closed, an electric glow-lamp pivotally mounted beneath said cover and a spring to project the same out 90 through the cover-opening when the cover is opened, electric connections from the battery 95

to the lamp, normally disconnected when the lamp is down and means for completing the circuit when the cover is opened and the lamp projected out in the manner and for the purpose substantially as described.

3. In a lamp the combination of a body having an electric battery therein, a spring-opened cover and a catch to retain the same closed, a glow-lamp pivotally mounted beneath said cover and means for projecting it out and completing the circuit to the battery when the said cover is opened, a fixed handle to the lamp-body and a pivotally-mounted handle

in proximity thereto, a nose or finger at the forward end of the said pivotally-mounted handle in proximity to the cover-catch and adapted to release the latter when the two handles are gripped substantially as described.

In witness whereof I have hereunto set my hand in presence of two witnesses.

MORITZ HAMMERSTEIN.
